by Ira Milton Jones
et Worley.

UNITED STATES PATENT OFFICE.

GEORGE HENRY WHEARY, OF RACINE, WISCONSIN, ASSIGNOR TO WHEARY TRUNK COMPANY, OF RACINE, WISCONSIN, A CORPORATION OF WISCONSIN.

BAGGAGE CARRIER.

Application filed June 8, 1927. Serial No. 197,380.

This invention relates to certain new and useful improvements in baggage carriers and has as an object the provision of a solid bottom wardrobe trunk of improved design 5 having the exterior appearance of a conventional type of trunk.

Another object of this invention resides in the provision of an improved baggage carrier which will be lighter than the baggage 10 carriers now in use and, at the same time, of sturdier construction.

Another object of this invention resides in the provision of an improved door type baggage carrier wherein the door is flush 15 with the outer surrounding surface.

Another object of this invention resides in the provision of an improved solid bottom baggage carrier having its opposed side panels fixed and its front and rear panels hinged 20 to form doors permitting access to either compartment and, at the same time, presenting an unbroken exterior appearance when the doors are closed.

One objectionable feature of baggage carriers of the door type is that access is had 25 to the drawer section from the narrow side instead of from the wide side as in the conventional wardrobe trunk construction and this invention has as an object the provision 30 of an improved solid bottom, door type trunk wherein access is had to the drawer section from its wide side, without sacrifice in strength or in any wise breaking the outward appearance of the trunk.

Another object of this invention resides 35 in the provision of an improved baggage carrier having one or more doors and a hinged top whereby closing of the hinged top locks the door or doors.

Another object of this invention resides in 40 the provision of an improved baggage carrier having a flush door provided with interlocking peripheral connections adapted to be under tension when the door is closed and 45 which will exclude foreign matter at the marginal edges of the door.

Another object of my invention resides in 45 the provision of an improved baggage car-

rier of the character described having a corner post over which a tubular member is 50 engaged to form a combination binding for the trunk corner and part of an interlocking connection with the adjacent edge of the trunk door.

And a further object of this invention resides 55 in the provision of a door trunk in which the doors are flush with the trunk exterior and are provided with concealed means for tying the edges of the doors to the trunk proper when closed to give added 60 strength thereto.

With the above and other objects in view which will appear as the description proceeds, my invention resides in the novel construction, combination and arrangement of 65 parts substantially as hereinafter described and more particularly defined by the appended claims, it being understood that such changes in the precise embodiment of the hereindisclosed invention may be made as 70 come within the scope of the claims.

In the accompanying drawings, I have 75 illustrated one complete example of the physical embodiment of my invention constructed according to the best mode I have so far devised for the practical application of the principles thereof, and in which:

Figure 1 is a perspective view of a trunk embodying my invention;

Figure 2 is a perspective view of my im- 80 proved trunk in open position, parts thereof being broken away to illustrate details of construction;

Figure 3 is a transverse sectional view 85 through Figure 1 on the plane of the line 3-3;

Figure 4 is an enlarged, fragmentary, sec- 90 tional view taken through Figure 1 on the plane of the line 4-4;

Figure 5 is a vertical sectional view taken 90 through Figure 3 on the plane of the line 5-5 and illustrating the door locking mechanism;

Figure 6 is a fragmentary view of one 95 portion of the corner post binding and reinforcing member;

Figure 7 is a fragmentary perspective view of one of the hinged lid actuated door locking devices, and

Figure 8 is a fragmentary sectional view 5 through Figure 2 on the plane of the line 8—8.

Referring now more particularly to the accompanying drawings, the numeral 5 designates the bottom or base panel of a baggage carrier which is preferably of one piece 10 and of a depth equal to the combined depth of the wardrobe and drawer compartments 6 and 7 defined by side panels or walls 8 and 9 and a central partition 10, access being had to the compartments through doors 11 and 12. Corner posts 13 and 13' 15 preferably of the construction illustrated in my Letters Patent No. 1,119,133, dated December 1, 1914, extend upwardly from the bottom 5 and the panels 8 and 9 are secured 20 between the corner posts 13 and 13', respectively by rivets or other means and bindings 14 and 14' extend about the corner posts 13 and 13', respectively, and over the marginal 25 edges of the panels 8 and 9, to which they are secured by rivets 15 to dress the trunk exterior and impart added strength thereto. The bindings 14 and 14' form part of reinforcing and interlocking dowel means for 30 the outer marginal edges of the door.

The doors 11 and 12 when closed form 35 the front and rear panels of the trunk and are flush with the corner posts in the manner of the panels 8 and 9. Hinges 16 pivotally mount the doors from the corner posts 13' and the hinges are arranged with their butts recessed to eliminate all objectional 40 projections. The doors are further provided with an interlocking connection with the posts 13', when closed, to exclude foreign matter.

Each door preferably terminates above 45 the bottom 5 a slight distance and the space therebeneath is filled by a panel 17 connecting the posts 13 and 13' and being reinforced by an improved corner piece 18 at the juncture of each corner post with the base and extending above the top of the adjacent panel 17. The corner pieces 18 50 have their inner upper corners cut away in register with the openings closed by the doors and the cut-out portions of the corner pieces carried by the posts 13' are filled by the parts 19 of the bottom hinges 16. The 55 cut-away portions of corner pieces 18 secured to the posts 13 are filled by plates 20 fixed to the lowermost, outer corners of the doors when closed, so that the continuity 60 of the corner pieces remain unbroken in appearance when the doors are closed.

A reinforcing binder 21 is secured over the outer and bottom marginal edges of each door, which is preferably formed from strip metal bent angularly along a longi-

tudinal line to form an end 22 for the door, then outwardly toward the front face 23 of the binder to form a bead 24 and then turned and extended inwardly over the door edge, as at 25, to, with the bead 24, form a channel 26, the binder then extending along the 70 door inner surface parallel with the outer portion 23, rivets 27 carrying out the effects of rivets 15, securing the binders to the doors.

As best illustrated in Figures 4 and 6, the 75 bindings 14 and 14' are of substantially tubular construction approximately conforming in transverse section to the cross section of the corner posts over which they are engaged from the top, being secured in place by the rivets 15 extending through the outer marginal edges thereof and the panels and by fastenings 28 securing the inner marginal portions thereof to the inner surface of the corner posts adjacent the side 85 panels. The binding 14 conforms with the curvature of the outer surface of the corner post 13 and is bent inwardly along the inwardly extended wall 29 thereof, as at 30, and then transversely along the transverse 90 wall 31 thereof, as at 32. From the wall 32, the binding is curved outwardly and toward the wall 30 and is then folded inwardly 95 upon itself along the wall 33 of the corner post to define a channel 34 and a bead 35 cooperating with the binder 21, bead 24 and channel 26, respectively.

The binding 14' is substantially identical 100 with the binding 14 with the exception of the specific shape of the bead and channel and that the wall 31' of the post 13' is set 105 inwardly beyond that of the corner post 13 by reason of the construction of the binder 21' secured over the inner marginal edge of the door.

The binding 21' is of channel shape having 110 its longitudinal marginal portions 36 and 37 embracing the outer and inner surfaces of the door and its end wall 38 the edge of the door, a bead 39 being formed 115 at the juncture of the walls 37 and 38 for engagement in the channel 34 of the binding 14'.

As will be evident, the bead and channel 120 36 of the bindings 14 and 14' are so formed that the beads 24 and 39 of the binders 21 and 21' have a comparatively snug engagement which is such that the door is yieldably secured closed, after the beads and channels are once engaged. The joint between the 125 bindings 14 and 14' and the binders 21 and 21' is further protected against foreign matter passing the same by suitable packing 40 inserted in the channels 34.

The binders 14 and 14' are secured over the 130 corner posts by being slipped thereover from the top prior to the mounting of the uppermost fittings or hardware, to be later de-

scribed, and completely encase the corner posts to give added rigidity thereto as well as provide the interlocking connections with the door when closed, and the outer surface 5 of the bindings 21 and 21' form continuations of the binding 14 and 14', respectively, so that a uniform appearance is obtained.

Suitable fittings 41 are secured at the tops of the corner posts and are formed with 10 dowel sockets 42 in which the dowel members 43 of corner members 44 of a hinged top or lid 45 engage, corner members 44 likewise having dowel members 46 engageable with dowel sockets 47 in members 48 fixed 15 to the upper corners of the doors, the members 48 cooperating to give a uniform appearance to the fittings 41. The lid or cover 45 is hinged to the panel 9 and is closed after the doors 11 and 12 have been closed and has 20 a peripheral valance 49 which engages over the top marginal edges of the panel 8 and doors 11 and 12 to secure the doors closed at their upper portions, there being means actuated by the movement of the lid over the 25 trunk to lock the outer and lower edges of the doors. The lid 45 may be locked by any conventional means such as a hasp 50 hinged thereto and engageable with a lock plate 51 carried by the panel 8. Each door has a vertical rod or bar 52 vertically slidably mounted adjacent its outer marginal edge by guides 53 with its upper end 54 in the path of a metal strike plate 55 carried by the lid. The lower end 56 of the bar is projectable 30 beyond the door bottom to engage a keeper 57 fixed to the adjacent panel 17 as best shown in Figure 5, a spring 58 normally urging the lock actuating bar upwardly so that opening of the lid or top automatically 35 permits the unlocking of the lower portion of the door. Added rigidity is imparted to the locking structure by a transverse member 59 extended from the locking bar and braced by a diagonal member 60 and from 40 which a locking member 61 depends. The member 61 is guided by a member 62 for engagement in a keeper 63 carried by the panel 17.

The locking bars 52 likewise provide for 45 locking the free ends of the doors, having locking members 64 projected laterally therefrom at intervals for engagement behind keepers 65 carried by the corner post 13. The members 64 engage the keepers 65 as the bar 52 is depressed by the closing of 50 the lid to thus firmly secure the marginal edges of the door to the adjacent corner post.

The drawer section 7 is provided with 60 drawers 66, the outer edges of which are provided with laterally projecting flanges 67, and the flanges of the drawers in line with the keepers 65 are notched, as at 68, to permit the movement of the drawers 65 therewith. The wardrobe section 6 of the

trunk, is likewise provided with a suitable trolley and hangers 69 and means may be provided in the outer lowermost portion thereof for mounting a removable shoe box or other container 70.

70

The partition 10 dividing the trunk into its respective compartments is preferably secured in place by angle irons or other means 71 carried by the panels 8 and 9 and provide the means for tying the side walls 75 together when the trunk is open, when the trunk is closed an extremely strong structure is obtained by reason of the doors 11 and 12 being tied together at all points.

It will also be apparent that the objections heretofore existing to trunks of the door type, such as the protruding of clumsy and awkward fittings and braces is entirely eliminated as the doors of the trunk are flush with the corner posts and firmly tie 80 the trunk parts together; that the doors have the appearance of the side panels of the trunk and further that the closing of the lid 45 automatically effects the complete locking of the doors and opening of the lid instantly unlocks the trunks.

What I claim as my invention is:

1. In a baggage carrier including side panels and corner posts between which the panels are secured, access being had to the 95 carrier interior between two corner posts, a door for closing the space between the corner posts, and means whereby the door is flush with the corner posts when closed.

2. In a baggage carrier including side 100 panels and corner posts to which the panel side marginal edges are secured, access being had to the carrier interior between two corner posts, a door for closing the space between the corner posts, means whereby the 105 door is flush with the corner posts when closed, and means along the marginal edges of the door when closed for excluding the entrance therewith of foreign matter.

3. In a baggage carrier including side 110 panels and corner posts to which the panel side marginal edges are secured, access being had to the carrier interior between two corner posts, a door for closing the space between the corner posts, means whereby the 115 door is flush with the corner posts when closed, a hinged cover closing the top of the carrier, and means operable upon movement of the hinged cover to closed position to lock the door.

4. In a baggage carrier, a solid bottom member, panels extending upwardly from the bottom member, a hinged lid closing the top of the carrier, means dividing the interior of the carrier into a wardrobe and a 125 drawer section, means hinging the front and rear panels for movement to and from closed position to permit access to the respective compartments, interlocking means between the marginal edges of the hinged panels and 130

the trunk corner posts, and means cooperating with said interlocking means to exclude foreign matter from entering the trunk past the hinged panels.

5. In a baggage carrier construction, a corner post member having recessed faces disposed at right angles with respect to each other in transverse section, a panel adapted to be secured to the corner post with its marginal edge secured to one offset of the corner post, and a door adapted when closed to abut the other offset whereby the outer surface of the door is flush with the outer surface of the corner post.
10. 6. In a baggage carrier construction, a corner post member having recessed faces disposed at right angles with respect to each other in transverse section, a panel to be secured to the corner post with its marginal edge engaging one offset, a door adapted when closed to abut the other offset whereby the outer surface of the door is flush with the outer surface of the corner post member, and a binding strip connecting the panel with 25 the corner post member and having a portion extended about the corner post.

7. In a baggage carrier construction, a corner post member having recessed faces disposed at right angles with respect to each other in transverse section, a panel adapted to be secured to the corner post with its marginal edge engaging one offset, a door adapted when closed to abut the other offset whereby the outer surface of the door is 30 flush with the outer surface of the corner post member, a binding strip connecting the panel with the corner post member and having a portion extended about the corner post, and cooperating means between the door and 35 binder providing an interlocking connection between the door and corner post member when the door is closed.

8. In a baggage carrier construction, a corner post member having recessed faces disposed at right angles with respect to each other in transverse section, a panel secured to the corner post with its marginal edge engaging one offset, a door adapted when closed to abut the other offset whereby the outer surface of the door is flush with the outer surface of the corner post member, and a metallic binder strip formed so as to 50 encase the post member, a part thereof being extended and connected with the panel and another part thereof engaging the adjacent door edge.

9. In a baggage carrier construction, a corner post member having recessed faces disposed at right angles with respect to each other in transverse section, a panel secured to the corner post with its marginal edge engaging one offset, a door adapted when closed to abut the other offset whereby the outer surface of the door is flush with the outer surface of the corner post member, a 60

metallic binder strip formed so as to encase the post member, and cooperating means between the strip and door providing an interlocking engagement therebetween when the door is closed.

70

10. In a baggage carrier having a one-piece bottom member, a pair of fixed panels extended from opposite sides of the bottom member, a partition member connecting the panels at a medial point and dividing the carrier into sections, doors hinged to the opposite sides of one of said panels and adapted to close the space therebetween, top cover means adapted to be closed over the carrier after the doors have been closed to lock the same at their upper portions, and means for locking the doors closed along their bottoms.

75

11. In a baggage carrier having a one-piece bottom member, a pair of fixed panels extended from opposite sides of the bottom member, a partition member connecting the panels at a medial point and dividing the carrier into sections, doors hinged to the opposite sides of one of said panels and adapted to close the space therebetween, top cover means adapted to be closed over the carrier after the doors have been closed to lock the same at their upper portions, and means for locking the doors closed along their free edges and their bottoms.

80

12. In a baggage carrier having a one-piece bottom member, a pair of fixed panels extended from opposite sides of the bottom member, a partition member connecting the panels at a medial point and dividing the carrier into sections, doors hinged to the opposite sides of one of said panels and adapted to close the space therebetween, top cover means adapted to be closed over the carrier after the doors have been closed to lock the same at their upper portions, and means for locking the doors closed along their free edges and their bottoms, said means being actuated upon closing of the top cover means.

85

13. In a baggage carrier of the class described, a pair of corner post members, a door member hinged to one of said corner post members, a locking bolt slidably mounted along the outer free edge of the door member, locking lugs carried by the bolt, keepers carried by the second corner post member and adapted to receive said lugs, and means for actuating said locking member to its operative position.

90

14. In a baggage carrier of the class described, a pair of corner post members, a door member hinged to one of said corner post members, a locking bolt slidably mounted along the outer free edge of the door member, locking lugs carried by the bolt, keepers carried by the second corner post member and adapted to receive said lugs, means for actuating said locking member to its operative position, a keeper adjacent the 105

110

115

120

125

130

bottom edge of the door member, and additional locking means carried by the bolt and engageable with the keeper.

15. In a baggage carrier of the class described, a pair of corner post members, a door member hinged to one of said corner post members, a locking bolt slidably mounted along the outer free edge of the door member, locking lugs carried by the bolt, keepers 10 carried by the second corner post member and adapted to receive said lugs, means for

actuating said locking member to its operative position, a keeper adjacent the bottom edge of the door member, additional locking means carried by the bolt and engageable 15 with the keeper, means normally urging the bolt to an inactive position, and a top cover for the carrier adapted in closing to move the bolt against its urging means.

In testimony whereof I hereunto affix my 20 signature.

GEORGE HENRY WHEARY.
